UNITED STATES PATENT OFFICE.

WILLIAM JAMES EVANS, OF NEW YORK, N. Y., ASSIGNOR TO MCKESSON & ROBBINS, OF SAME PLACE.

DESIGN FOR A NASAL CUP.

SPECIFICATION forming part of Design No. 34,708, dated July 2, 1901.

Application filed May 28, 1901. Serial No. 62,292. Term of patent 14 years.

To all whom it may concern:

Be it known that I, WILLIAM JAMES EVANS, a subject of the King of Great Britain, residing at New York, in the county of New York and State of New York, have invented and produced a new and original Design for a Nasal Cup; and I do hereby declare the following to be a full, clear, and exact description of the same, reference being had to the accompanying specification, forming a part thereof.

This invention relates to a new and original design for nasal cups, and it is embodied in the construction shown in the accompanying drawings and herein described.

In the drawings, Figure 1 represents the design in side elevation. Fig. 2 is a rear elevation of the same.

The general features of the design consist in a cup-body A of substantially cylindrical formation and oblong. The upper edge of the cup is fashioned with a shallow curved front depression B, the walls of which emerge into the side edges C. The rear edge of the cup is gradually depressed into a deep depression D, the walls of which converge from the upper side edges of the cup gradually.

The general characteristic features of the design which constitute the essential appearance and feature is a cup having a peculiarly-formed upper edge with a shallow front and deep rear depression.

Having thus described the invention, what I claim as new, and desire to secure by Letters Patent, is—

The design for a nasal cup, substantially as shown and described.

In testimony whereof I affix my signature in presence of two witnesses.

WILLIAM JAMES EVANS.
